(57) **CLAIM**

The ornamental design for a cereal food piece, as shown and described.

DESCRIPTION

FIG. 1 is a front, top and right side perspective view of a cereal food piece according to our design;

FIG. 2 is a front elevation view thereof;

FIG. 3 is a left side elevation view thereof;

FIG. 4 is a rear elevation view thereof;

FIG. 5 is a right side elevation view thereof;

FIG. 6 is a top plan view thereof;

FIG. 7 is a bottom plan view thereof; and,

FIG. 8 is another front, top and right side perspective view thereof, shown in an environment of use.

The less concentrated stippled shading and more concentrated stippled shading areas shown in FIGS. 1–8 represent contrasting appearances. The broken lines shown in FIGS. 3, 5, 6 and 7 illustrate portions of the cereal food piece that form no part of the claimed design. The broken lines in FIG. 8 illustrate environment that form no part of the claimed design.
